Attorney

UNITED STATES PATENT OFFICE.

WILLIAM O. BICE, OF LOGAN, IOWA.

CLOTHESPIN.

Application filed February 3, 1923. Serial No. 616,745.

To all whom it may concern:

Be it known that WILLIAM O. BICE, a citizen of the United States, residing at Logan, in the county of Harrison and State of Iowa, has invented certain new and useful Improvements in Clothespins, of which the following is a specification, reference being had therein to the accompanying drawing.

The invention relates to clothes pins, and has for its object to provide a device of this character comprising a pair of members slidably mounted and keyed on a shaft and normally forced together by means of coiled springs interposed between the members and heads carried by the shaft. The members have bevelled edges so that the same can be forced over a clothes line and clothes thereon against the action of the springs until the line is received in registering recesses in the members.

A further object is to form the members disc shaped, and to provide their inner faces with registering rectangular shaped grooves for the reception of the clothes line, the corners of the rectangular shaped grooves extending through the outer sides of the disc shaped members.

A further object is to provide a clothes pin comprising registering elongated members in pairs at right angles to each other, which members are slidably keyed on a shaft and movable against the action of coiled springs, one member forming a handle when the other members are used for clamping purposes.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a perspective view of the clothes pin.

Figure 2 is a side elevation of the clothes holding device.

Figure 3 is a vertical transverse sectional view through the device taken on line 3—3 of Figure 2.

Figure 4 is a perspective view of another form of clothes pin.

Figure 5 is a vertical transverse sectional

view through the clothes pin shown in Figure 4, taken on line 5—5.

Referring to the drawing, the numeral 1 designates a clothes line clamping device, which device comprises round disc shaped members 2, which are in registration with each other. The disc shaped members 2 are slidably mounted on an axially disposed shaft 3, and are keyed thereon by means of a key 4 for preventing rotation of the discs in relation to each other. The ends of the shaft 3 extend beyond the outer faces of the discs 2 and are provided with heads 5. Interposed between the heads 5 and the outer faces of the discs 2 are coiled springs 6, which spring normally maintain the discs 2 in close engagement with each other for clamping a clothes line and clothing in the registering straight sections 7 of rectangular grooves 8 which are preferably semicircular shaped in cross section and are carried by the inner faces of the disc shaped members 2. The rectangular shaped grooves 8 register with each other and are maintained in registration by the key 4, which prevent rotation of the discs 2 in relation to each other. The corners 9 of the registering rectangular shaped grooves 8 extend through the outer sides of the discs 2 and consequently, when a clothes line is forced through or between the discs in engagement with bevelled edges 10 thereof, the clothes line will be received in the adjacent straight portions 7 of the grooves 8 and will extend through the corners 9 and be securely clamped and held by the expansive action of the coiled springs 6.

It will be seen that the clothes line clamping device may be easily and quickly applied to a clothes line and that a line and piece of clothing carried thereby may be securely clamped and held. It will also be seen that the device is positive in its operation and the parts reduced to a minimum.

Referring to the modified form shown in Figures 4 and 5, the device comprises a shaft 3^a on which is slidably keyed by means of a key 4^a, clamping members 11 and 12, which members are disposed at a right angle to each other and in pairs. The clamping members 11 are elongated and have their ends bevelled at 13, so that a clothes line can be forced between the same to assume a position

in the registering recesses 14 where it will be securely held by the action of the coiled springs 15, which are interposed between the heads 16 carried by the shaft 3^a and the outer members 11 and 12. The members 11 and 12 are disposed at a right angle to each other and consequently when a line is forced between the ends of either of the members the other members will be in a position to be used as a handle by the operator. It will also be seen that the device is simple in construction and positive in its operation.

The invention having been set forth what is claimed as new and useful is:

15. 1. A clothes line pin comprising a pair of discs, a shaft extending through said discs, said discs being slidably keyed on the shaft, coiled springs surrounding the shaft, said coiled springs being interposed between 20 headed members carried by the ends of the shaft and the outer faces of the discs, the inner faces of said discs being provided with

registering rectangular shaped grooves having their corners extending through the outer edges of the disc.

- 25 2. A clothes line pin comprising a pair of round disc shaped members, a shaft extending through said discs axially, said discs being slidably keyed on the shaft, headed members carried by the outer end of the shaft, coiled springs interposed between the headed members and the outer faces of the discs and normally maintaining the same in engagement with each other, the outer adjacent edges of the discs being inwardly bevelled, rectangular shaped grooves in the inner faces of the discs in registration with each other, said rectangular shaped grooves having their corners extending through the bevelled edges of the discs.

30 35 40 In testimony whereof I hereunto affix my signature.

WILLIAM O. BICE.
